(57) **CLAIM**

The ornamental design for a terminal with a rectangular edge protrusion, as shown and described.

DESCRIPTION

FIG. 1 is a rear, side perspective view of a terminal with a rectangular edge protrusion;

FIG. 2 is a front, side perspective view of the terminal with a rectangular edge protrusion;

FIG. 3 is a front view thereof;

FIG. 4 is a rear view thereof;

FIG. 5 is another rear, side perspective view thereof;

FIG. 6 is another front, side perspective view thereof;

FIG. 7 is a top view thereof;

FIG. 8 is a bottom view thereof;

FIG. 9 is a side environmental view thereof illustrating the terminal in a connector housing; and,

FIG. 10 is a side environmental view thereof with a laterally inward facing screw in position in a connector housing. In the drawings, the broken lines depict environment that form no part of the claim.
